UNITED STATES PATENT OFFICE.

JAMES P. ELMER, OF ST. PAUL, MINNESOTA.

INSULATED CAR.

1,002,572.

Specification of Letters Patent. Patented Sept. 5, 1911.

Application filed January 13, 1911. Serial No. 602,416.

To all whom it may concern:

Be it known that I, JAMES P. ELMER, a citizen of the United States, residing at the city of St. Paul, county of Ramsey, and State of Minnesota, have invented a new and useful Improvement in Insulated Cars, of which the following is a specification.

My invention relates to improvements in the construction of insulated cars.

Broadly its object is to combine an all steel or iron frame with an insulated body inclosed in said frame but not bolted or bonded thereto. I thus eliminate the use of heat conducting connections between the two sections of the structure, and by building and maintaining the insulated freight chamber independently of the steel supporting frame, I secure the rigidity and strength of the latter with the insulating advantages of non-metallic construction. I also secure many other advantages over other plans of construction. The under frame and truss body frame are made from regular structural steel shapes, and a well designed all-steel frame car of this construction does not weigh more than a wooden frame car of equal capacity, and in most cases less. The load carrying steel frame is entirely outside of the insulated car body, and is consequently open to inspection, and easily accessible for repairs.

Figure 1 shows a side elevation of my improved insulated car, Fig. 2 shows an end elevation of the same, and Fig. 3 shows a sectional view taken on the line 3—3 of Fig. 1.

Referring to the accompanying drawings the sills of the steel frame, indicated by the reference numeral 10, are mounted on the bolsters 11, which are arranged in the usual manner on the trucks 12. The upright channel shaped posts 13 and the diagonal channel shaped braces 14, on the sides of the frame are riveted at one end to the sills 10 and at the other to the plates 16. The upright channel shaped posts 17 and the diagonal channel shaped braces 18 at the ends of the frame are riveted at one end to the sill 10 and at the other to the plate 16 as shown in Figs. 1 and 2. I have provided

within the frame an insulated freight chamber. The sub-floor 21 of said chamber rests on the sill 10 and the plates 19 which are supported on the bolsters 11. The floor 20 is spaced apart from the sub-floor 21, by the longitudinal sills 22 and the spacing strips 23. A layer of water proof material 24 arranged between the sills 22 and the spacing strips 23 forms an air space 25 below the floor 20 and prevents moisture from penetrating the layers of insulating material 26 and 27, which are spaced apart by the sheathing 28 and 29 to form an air space 30. The sides, ends and roof of the freight chamber are similarly constructed. The sides and ends are built on the floor inside of the posts 13 and braces 14, and comprise two layers of sheathing 31 and 32, and a layer of insulating material 33 spaced apart to form an air chamber 34. The ceiling supported by the sides and ends of the freight chamber conforms with the hereinafter described roof on the frame, and is a continuation of the sides and ends of the freight chamber. The ice box 35 is arranged at the top of the freight chamber in the ordinary manner and is accessible through the hatches 36 which extend from the freight chamber through the roof of the car. The doors 37 are arranged at the sides of the freight chamber and provide access thereto. I have provided a roof for the frame, comprising a series of carlines 38 riveted at the ends to the plate 16 as shown in Fig. 3. The roof boards 39 are supported by the carlines 38 and the purlines 40 which are mounted on said carlines.

While I have shown and described a refrigerator car it is obvious that my method of construction may be applied to other classes of cars and particularly to heater cars without departing from the spirit of my invention.

Having described my invention, what I claim as new and desire to protect by Letters Patent is:

1. The combination of a self sustaining inner wooden car body comprising roof, floor and sides and an all steel car frame disconnected from said body but surround-

ing, freely supporting and substantially filled by said body.

2. In a refrigerator car an all steel frame in combination with an insulated self supporting interior car body, said body including floor and sides and substantially filling said frame.

In testimony whereof, I have signed my name to this specification in the presence of two subscribing witnesses.

JAMES P. ELMER.
